US0D1079654S

(12) **United States Design Patent** (10) Patent No.: **US D1,079,654 S**
(45) Date of Patent: ** Jun. 17, 2025

(54) **MEDICAL DEVICE CONNECTOR**

- (71) Applicant: **Physio-Control, Inc.**, Redmond, WA (US)
- (72) Inventors: **Christopher Alviar**, Seattle, WA (US); **Neal Clark**, Snohomish, WA (US); **Barry Curtin**, Seattle, WA (US); **Neil McIlvaine**, Seattle, WA (US); **Peter Nazaroff**, Redmond, WA (US); **Zack Pahlman**, Redmond, WA (US); **Jeremy Wong**, Redmond, WA (US); **Christian Schneider**, Redmond, WA (US)
- (73) Assignee: **Physio-Control, Inc.**, Redmond, WA (US)
- (**) Term: **15 Years**
- (21) Appl. No.: **29/914,076**
- (22) Filed: **Oct. 12, 2023**

Related U.S. Application Data

- (63) Continuation of application No. 29/708,062, filed on Oct. 2, 2019, now Pat. No. Des. 1,013,640.
- (51) **LOC (15) Cl.** 13-03

CLAIM

The ornamental design for a medical device connector, as shown and described.

DESCRIPTION

FIG. 1 is a side view of a medical device connector;

FIG. 2 is a front perspective view thereof;

FIG. 3 is a top view thereof;

FIG. 4 is a front view thereof;

FIG. 5 is a back view thereof; and,

FIG. 6 is a side view thereof.

The broken lines in the drawings illustrate portions of the medical device connector that form no part of the claimed design. The dot-dashed broken lines represent boundaries of the claimed design and form no part of the claimed design.

1 Claim, 4 Drawing Sheets
